MULTI-CONTACT DIELECTRIC HOUSING FOR RECEIVING AN OPTICAL DISPLAY READOUT DEVICE

Abul Abbas Mesbahuddin Ahmed, Harrisburg, Pa.,
assignor to AMP Incorporated, Harrisburg, Pa.

Filed Feb. 23, 1973, Ser. No. 335,218

Term of patent 14 years

Int. Cl. D13—03

U.S. Cl. D26—1 B

Fig. 2

FIG. 1 is a perspective view of a multi-contact dielectric housing for receiving an optical display readout device showing my new design. FIG. 2 is a front elevational view thereof; FIG. 3 is a top-plan view thereof; FIG. 4 is a bottom-plan view thereof; FIG. 5 is a rear elevational view thereof; FIG. 6 is a side elevational view thereof.

The nature of the invention resides in an ornamental frame for displaying an optical numerical display device utilized in a digital readout-type calculator.

I claim:

The ornamental design for a multi-contact dielectric housing for receiving an optical display readout device, as shown and described.
